UNITED STATES PATENT OFFICE

WALTER F. FOSTER, OF SAN FRANCISCO, CALIFORNIA, ASSIGNOR TO CONDOR COMPANY,
A CORPORATION OF NEVADA

DOORCHECK

Application filed June 6, 1931. Serial No. 542,592.

The present invention relates to a door check of the dashpot or fluid resistance type, which is adapted for concealment in the door casing or in the rear stile of the door itself, and is preferably attached to or combined with the door hinge.

The principal object of the invention is to provide a door check of the described type in which all possibility of leakage of the 10 checking fluid is eliminated, and in which the fluid is entirely contained within a closed shell to prevent loss by evaporation. The achievement of these objects enables the use of such fluids as a mixture of alcohol and glycerine, for example, whose viscosity 15 changes very little with variations in temperature, thereby eliminating the necessity for frequent adjustment. It also prevents loss of fluid with consequent necessity for 20 refilling, and prevents the unsightly effect caused by even a small leakage of the operating fluid.

Other objects of the invention are to provide a device which is simple and inexpensive 25 to manufacture and assemble, which is easy to adjust to varying degrees of resistance, and which is capable of positive operation over a long period of time without attention.

Although the preferred location of my 30 door check is in association with the door hinge, as described and illustrated herein, it should be understood that it may be located in any position in which its construction will 35 permit suitable operation. It should also be noted that the form, construction and arrangement of the several parts, hereinafter described and shown in the accompanying drawing, may be varied within the limits of 40 the claims hereto appended, without departing from the spirit of the invention as set forth in said claims.

A preferred form of the invention is illustrated in the accompanying drawing in 45 which

Fig. 1 is a longitudinal vertical section of the door check.

Fig. 2 is a transverse section on the line 2-2 of Fig. 1.

50 Figs. 3 and 4 are transverse sectional de-

tails taken on the respective lines 3-3 and 4-4 of Fig. 1, and enlarged.

Fig. 5 is a part sectional plan view showing a preferred method of mounting my door check.

In the drawing, and referring for the moment to Fig. 5 thereof, the reference numerals 1 and 2 designate portions of a door and its frame or casing. Either may be regarded as the door and the other as the casing. 3 and 3' 60 are the two members or plates of the door hinge, herein shown as of the butt type. 4 is a stud projecting from and preferably secured to the hinge plate 3. 5 is the shell of the door check, which is of greater height 65 than width, and is adapted for insertion in the door (or casing) 2. This shell has a front wall or face 6, Fig. 1, adapted to lie beneath or behind the hinge plate 3', and provided with apertured lugs 7 by which it is 70 bolted to said hinge plate 3', as indicated at 7' in Fig. 5.

In the upper portion of the shell 5 is a guide barrel 8, Fig. 1, having a forward portion 9 of reduced diameter. A plunger 10 operates 75 within the barrel 8 and is carried upon the rear end of a stem 11 which extends through the guide 9 and projects forwardly therefrom for contact with the opposing stud 4, as shown in Fig. 5, so that the stem 11 and plunger 10 80 are moved rearwardly, that is, toward the right in Fig. 1, by the closing of the door.

In the lower portion of the shell 5 is a cylinder 12 in which the checking fluid is compressed by the forward movement of a piston 13. The piston 13 is connected with the plunger 10 by a link 14 and a lever 15, the latter being pivoted upon a pin 16. The pin 16 is preferably formed, as shown in Fig. 2, with a threaded head portion 17 adapted to be 85 screwed into a suitable recess in the side of the shell 5. The cylindrical portion of the pin 16 passes through the lever 15 and is seated in opposing bosses 18 projecting inwardly 90 from the side walls of the shell. The upper end of the lever 15 extends through a longitudinal slot 19 in the bottom of the guide barrel 8 and bears against the rear face of the plunger 10. A spring 20 moves the plunger 95 forwardly and the piston 13 rearwardly. 100

The forward end of said spring is coiled into a ring of reduced diameter and secured beneath the head of a screw 21, which is screwed into the forward wall of the shell from the rear. The rear end of the spring 20 is provided with an elongated loop 22 surrounding the lever 15 and retained in position thereon by a notch 23.

The forward end of the cylinder 12 is closed, preferably by a screw plug 24 and a suitable gasket 25. A port 26 leads upwardly from the forward end of the cylinder 12 and communicates with a rearwardly extending passage 27 in which is formed a valve seat 28. A needle valve 29 is positioned within the passage 27 for contact with the seat 28 to regulate the effective area of said passage. The forward end of the needle valve 29 is provided with a threaded head 30, which is accessible from the front face 6 of the shell upon the removal of a sealing plug 31. The needle valve 29 is preferably provided with a tapering V-shaped slot 32 which increases in area toward the rear end of said valve. The purpose of this slot is to decrease the variation in the effective area of the valve upon any given movement of the needle, in other words, to provide a fine adjustment of the valve area with considerable movement of the needle.

The piston 13 is provided with a check valve comprising a disk 33 positioned to cover and uncover a plurality of ports 34. The disk 33 is freely mounted upon a stem 35 and is held against its seat by a spring 36. When the piston 13 moves rearwardly under the impelling action of the spring 20, that is, upon the opening of the door, the fluid flows freely through the ports 34 into the cylinder 12, but upon the closing of the door, when the piston 13 moves forwardly, the fluid within said cylinder can escape only through the needle valve controlled passage 27. Adjustment of the needle valve 29 varies the resistance of the fluid to said forward movement of the piston. The cylinder 12 has a longitudinally tapered V-shaped groove 37 in its wall, extending forwardly from its rear end and decreasing in area toward the front. This groove bypasses a portion of the checking fluid around the piston during the first portion of its forward movement, such by-passing effect decreasing as the piston moves forwardly. The resistance to the closing of the door therefore takes effect gradually, in order to relieve the hinges of any sudden strain.

The interior of the shell 5 forms a reservoir for a supply of the checking fluid. A filling aperture 38, closed by a screw plug 39 in the face of the shell, is provided for the introduction of the fluid thereinto. The fluid normally stands in the shell at a level represented by the broken line 40.

It will be observed that the fluid is entirely within the lower portion of the shell 5, and

never rises into the plunger barrel 8. Moreover, there is little pressure in the reservoir portion of the shell. Therefore, any simple packing, as indicated at 41, around the plunger stem 11, is sufficient to prevent such fluid as may splash up on to the plunger and its stem from leaking out around said stem. It is to be noted, however, that the packing 41 seated around the stem 11, between the annular opposing faces or shoulders of the piston 10 and the barrel abutment has the further important function of positively preventing leakage of the internal fluid under positional changes of the device other than the position just mentioned in which the fluid lies in the lower portion of the shell. Such other changes of position are those which, in preliminary handling, packing, shipping, preparation for setting, etc., may have the effect of temporarily inverting, wholly or partly, the device and causing the fluid to enter the barrel 8. In any such case the packing 41 provides for a perfect seal against fluid leakage. It is also to be noted that the entire shell is closed so that there can be no evaporation of the fluid. The piston and cylinder are in the lowest portion of the shell, entirely submerged in the fluid at all times, so that the checking action of the fluid cannot be lessened or destroyed by air bubbles in the cylinder 12.

The rear end of the shell 5 is preferably a removable plate 42, secured in place to make a fluid tight joint by any suitable means such as screws indicated at 43. This construction permits the shell to be cast and machined with a minimum amount of labor. The barrel 8 can be bored in from the rear end, the guide portion 9 can be bored straight through, and the cylinder 12 can also be bored straight through to insure its accuracy.

In assembling the device, the plunger 10 and its stem 11 are first put in place from the rear end of the shell. The spring 20 is then secured to the front wall of the shell by means of a screwdriver extended into it. The piston 13, the link 14 and the lever 15 are then assembled outside the shell and are introduced into it from the rear, the upper end of the lever 15 being passed through the loop 22 at the rear end of the spring 20. The pivot pin 16 is then inserted from the side. The forward end of the cylinder 12 is closed by the screw plug 24 and gasket 25. The needle valve 29 is placed in position from the front, and the rear plate 42 is attached to the rear end of the shell. After the device has been filled with fluid and the needle valve adjusted to the proper point, the screw plug 31 is inserted and screwed home against a gasket 44 to prevent leakage of fluid around the head of said needle valve. No further attention need be given the device except to vary the adjustment of the needle valve as may be required to suit the particular conditions under

which the device is operated. It is understood that the hinge plate 3' is provided with apertures, not shown, through which the filling plug 39, the needle valve seating plug 31, and the cylinder head plug 24 are accessible for removal when necessary.

The lever connection between the plunger and piston not only permits the plunger to be positioned above the level of the liquid in the shell, but also allows said plunger to have a longer stroke in relation to that of the piston. By the use of the stud 4, which extends into the guide 9 when the door is closed, contact can be established between stud and plunger when the door is nearly 90° open, thus keeping the door under control throughout half of its total movement. Since comparatively few doors are opened more than 90°, my check provides control throughout the most used portion of the door's movement.

I claim:—

1. A door check comprising a fluid containing shell having greater height than width and adapted for insertion in a door or casing, said shell having a guide barrel in its upper portion and a cylinder in its lower portion, said barrel extending from front to rear of said shell and having a longitudinal slot in its bottom wall, and said cylinder communicating with the interior of said shell; a plunger movably mounted in said barrel and projecting through the front wall of said shell; a piston movable in said cylinder and adapted to circulate the fluid between said cylinder and the interior of said shell; a lever connecting said plunger and said piston, said lever being pivotally mounted within said shell and having its upper end operating through the slot in said barrel and engaging the rear end of said plunger; and means for restricting the circulation of said fluid.

2. A door check comprising a fluid containing shell having greater height than width and adapted for insertion in a door or casing, said shell having a horizontal guide barrel in its upper portion and a cylinder in its lower portion, said cylinder communicating with the interior of the shell; a plunger movably mounted in said barrel and projecting through the front wall of said shell; a piston movable in said cylinder and adapted to circulate the fluid between said cylinder and the interior of said shell; a lever pivotally mounted between its ends within said shell, the lower end of said lever being connected with said piston and its upper end bearing against the rear end of said plunger; a tension spring connecting the upper end portion of said lever with the front wall of said shell; and means for restricting the circulation of said fluid.

3. A door check comprising a fluid containing shell having a socket in its wall; a cylinder within said shell having a passage connecting with the interior of the shell; an ad-

justable needle valve adapted to control said passage, said valve having an adjusting head seated within said socket; a closure for said socket adapted to cover said head and prevent exterior leakage of fluid through and from said socket; a piston in said cylinder; and means for moving said piston from outside said shell.

4. A door check comprising a shell of greater height than width and having a front wall and an open rear end, said shell further having a horizontal guide barrel formed in its upper portion and a horizontal cylinder formed in its lower portion, said barrel and said cylinder extending through said front wall, and said cylinder communicating with the interior of said shell; a separable closure for the rear end of said shell adapting it to contain a supply of fluid; a closure for the front end of said cylinder; a plunger movable in said barrel and extending through the front wall of the shell; a piston movable in said cylinder; a lever pivotally mounted within said shell connecting said plunger with said piston; and means for restricting the flow of fluid between said cylinder and the interior of the shell upon movement of said piston.

5. A door check comprising a fluid-containing shell having a guide barrel in its upper portion communicating with the shell interior, one end of said barrel opening through the front wall of the shell and being of reduced diameter to form an annular internal shoulder; a plunger slidable in the barrel, said plunger having a shoulder adapted to abut against the shoulder of said barrel and a reduced stem portion slidable through the reduced portion of the barrel; a packing interposed between said shoulders; a cylinder in the lower portion of the shell communicating with the shell interior; a valved piston slidable in the cylinder; and a lever pivoted within the shell with its ends engaging said plunger and piston respectively.

6. A door check comprising a fluid containing shell adapted for insertion in a door or casing, said shell having a guide barrel in its upper portion extending from front to rear, and the rear portion of said barrel being of larger diameter than its forward portion and having a longitudinal slot formed in its bottom wall; a pressure cylinder in the lower portion of said shell communicating with the interior thereof; a plunger slidably mounted in said barrel, the forward portion of said plunger extending through the reduced forward portion of said barrel, and the rear portion of said plunger being of larger diameter than said forward portion and operating in the slotted rear portion of said barrel; a piston movable in said cylinder to circulate the fluid between said cylinder and the interior of the shell; a lever connecting said plunger and said piston, said

lever being pivotally mounted within said shell and operating through the slot in said barrel; and means for restricting the circulation of said fluid.

5 In testimony whereof I have signed my name to this specification.
